UNITED STATES PATENT OFFICE.

FRANK S. BALDWIN, OF DETROIT, MICHIGAN.

LUMBER-MEASURE.

SPECIFICATION forming part of Letters Patent No. 367,261, dated July 26, 1887.

Application filed February 18, 1887. Serial No. 222,026. (No model.)

To all whom it may concern:

Be it known that I, FRANK S. BALDWIN, a citizen of the United States of America, residing at Detroit, in the county of Wayne and State of Michigan, have invented certain new and useful Improvements in Lumber - Measures, of which the following is a specification, reference being had therein to the accompanying drawings.

10 My invention relates to improvements in lumber-measures, and more particularly to the measures shown and described in my Letters Patent No. 138,310, dated April 29, 1873.

The invention consists in the combination, 15 with the set of registering-dials that register the aggregate measurements, of an auxiliary set of dials for registering a single measurement, and adapted, as the tape-line is withdrawn within the case, to return to zero.

20 The invention consists, further, in certain details of construction and combinations of parts, which will first be described in connection with the accompanying drawings, and then clearly pointed out in the claims.

25 Figure 1 of the drawings is a plan view of my improved lumber-measure, the registering-dials being shown in dotted lines. Fig. 2 is a bottom plan view with the bottom of the casing removed and the reel and ratchet-disk 30 partly broken away. Fig. 3 is a transverse sectional elevation taken on the line $y-y$ of Fig. 2. Fig. 4 is an edge view, partly sectional, of the reel. Fig. 4^a is a plan view of the reel on a smaller scale. Fig. 5 is an enlarged detail 35 view showing the mechanism for shifting the pinion that engages with the cone of gears. Fig. 6 is a plan view of the yoke as attached to the sliding shaft. Fig. 7 is an edge view of the yoke as attached to the sliding shaft.

40 Referring to the drawings, A is the case. B represents the wheel, turning loosely on axle C, journaled in the sides of the case, the reel bearing a tape-line, D, preferably of spring-steel.

45 In my patent measure above alluded to the reel was made up of a hub, radial spokes, and a broad rim, on which the tape-line was wound. The objections to that reel are, that it is expensive to manufacture, and also that it is 50 necessary to rivet the end of the tape-line to the rim, which renders renewal of the tape, when

worn out, very inconvenient. In the present instance I construct the reel of two metallic circular plates, b b, each having a rim, b', stamped up from the body of the plate, and 55 the two plates united by solder or otherwise, as shown in Fig. 4. A hub, b², on one side of the reel, is secured in a perforation in the web of the reel. In order to secure the end of the tape-line to the reel, I cut a transverse slit 60 through the rim, as at b³, and perforate the web of the reel immediately under the slit, as at b⁴, into which perforation and slit the doubled or hooked end of the tape-line is inserted. The body of the reel being solid, it 65 cannot spring and thereby affect the accuracy of a measurement when the line is being drawn out, as would be the case if the rim of the old reel were cut through.

E represents a spring-coil on one side of the 70 reel for winding the tape-line, one end of the spring being secured to the hub and the other end to a stud, e, fixed in the case.

F represents a ratchet-disk, which, like the reel, turns loosely on axis C, and is locked to 75 the reel by a pin, f, projecting from the latter. (Shown in Fig. 2, but not in Fig. 3.)

G represents a cone of gears rigidly secured to disk F, for transmitting motion to registering-dials of the usual construction, of which 80 there is a main set, H, for registering the aggregate of a number of measurements, and also an auxiliary set, I, for registering a single measurement, h² indicating the units-dial, h' the tens-dial, and h the hundreds-dial in the 85 main set, and i the units-dial and i' the tens-dial in the auxiliary set. These dials are arranged immediately under the top plate of the case, the said plate being perforated, as shown in Fig. 1, to expose to view the figures thereon. 90 The dials are operated by a train of gears and pins, as follows:

1, 2, 3, 4, and 5 represent the shafts upon which the dials and their operating mechanism are mounted. Shaft 1 bears the units-dial i of the auxiliary set, a pin, 9, for moving the tens-dial i', and a gear-wheel, 6, all of which are rigidly fixed to the shaft. Shaft 2 bears the tens-dial i', a toothed wheel, 10, with one of whose teeth pin 9 engages at each revolution of shaft 1, and a gear-wheel, 7, (shown in full and dotted lines in Fig. 2,) loosely mounted 95 100

and gearing with wheel 6. Shaft 3 bears the units-dial h^2 of the main set, a pin, 11, for moving the tens-dial h' , a ratchet-toothed wheel, 12, and the gear-wheel 8 (also shown in full and dotted lines in Fig. 2) gearing with wheels 6 and 7 and provided on its inner side with pawls 13 for engagement with the teeth of wheel 12, as seen in Fig. 3. The units-dial h^2 has ratchet-teeth formed on its periphery, 10 with which a pawl, t , attached to the cap-plate, engages to prevent backward rotation of the dial, which, together with pin 11 and wheel 12, is rigidly fixed to shaft 3, while the gear-wheel 8 is loosely mounted thereon. Shaft 4 bears 15 the tens-dial h' of the main set, a toothed wheel, 14, with which pin 11 engages at each revolution of shaft 3 to move said dial, and a pin, 15. Shaft 5 bears the hundreds-dial h of the main set and a toothed wheel, 16, with 20 which pin 15 engages at each revolution of shaft 4 to move said dial. The main set of dials are provided with thumb-buttons c for turning them by hand, when desired.

K represents a broad pinion loosely journaled on a stud fixed in the case, which pinion transmits motion to the registering-train, and in turn motion is transmitted to this pinion by means of a narrow pinion, L, loosely journaled on the end of a transversely-movable shaft, M, extending through a slot, a , in the case. The inner end of this shaft has flattened sides, as shown, while its outer end is round and provided with a stud, m , which engages with a spirally-slotted sleeve, m' , enclosing that end of the shaft and having a flange, m^2 , on its inner end. Over this sleeve is placed another sleeve, m^3 , formed integral with the setting-disk, presently to be described, the two sleeves being secured together by a 40 screw, m^4 .

Shaft M is held in its proper relative position in slot a in the case, and at the same time is prevented from turning by means, preferably, of a yoke, N, having an elongated slot in one end for fitting over the inner end of the shaft, and a perforation in its other end to fit over the arbor-carrying pinion K. In order that this yoke may not spring and bind in operation, instead of making it throughout 50 its length of just sufficient thickness to lie conveniently alongside the flange m^2 on sleeve m' , as in my patented measure above mentioned, I make it as thick and rigid as possible and reduce that portion which fits shaft M only 55 sufficient to equal the thickness of the flange on the sleeve, as shown in Fig. 7, the flange in this way serving as a washer.

O represents the setting-disk, for setting pinion L into engagement with any desired portion of the cone of gears. This disk has recesses of varying depths in its periphery, and these recesses are numbered according to the lengths of measurements it is desired to make—in this instance ten, twelve, fourteen, sixteen, 65 and eighteen feet, the deepest notch being for the least number of feet, and these notches engage with a stud, o , on the case. The disk

when set is prevented from becoming disengaged from the stud by a pin, p , taking into a perforation, o' , in the disk near each recess, 70 the pin being secured to a spring-plate, P, secured to the under side of the top plate of the case, and provided with a stud, p' , extending through the top plate and bearing a push-button, p^2 , on its outer end. 75

It will be observed, on referring to Figs. 1 and 2, that the setting-disk is adjusted for measurements of fourteen feet. Now, as the cone of gears and the ratchet-disk are secured together, and the latter is locked to the reel, they 80 all turn together, so that as the tape-line is drawn out the cone transmits motion, through pinions L and K, to gear-wheels 6, 7, and 8. As wheel 6, pin 9, and dial i are all fixed rigidly to the shaft, they all partake of the movements of pinions L and K. Gear-wheel 7 is loose on shaft 2, and consequently has nothing to do with the movement of the tens-dial h' , that being accomplished by the engagement of pin 9 with wheel 10. Gear-wheel 8 is also loose 85 on its shaft; but in its forward movement its pawl 13 engages with wheel 12 and carries it, together with pin 11 and the units-dial h^2 of the main set, around with it, the pawl t riding freely over the teeth of the dial. Pin 11 on shaft 3 engages with wheel 14 on shaft 4 and moves dial h' , and pin 15 on shaft 4 engages with wheel 16 on shaft 5 and moves dial h . When a measurement is made, the number of feet will appear on the auxiliary dials and also 90 on the main dials. Then, as the tape is being wound up, the dials of the former set will be moved back to zero by the backward turning of wheels 6, 7, and 8; but the dials of the main set will remain stationary, being held in that 95 position by pawl t , engaging with the teeth on dial h^2 , as seen in dotted lines in Fig. 1 and in full lines in Fig. 2. Another measurement 100 made, it will again appear singly on the auxiliary dials; but the aggregate of the two measurements will appear on the main set, and so on. 105

If it is desired to measure different lengths—say ten feet—the setting-disk is turned until the recess marked 10 is engaged by the stud o , 110 and in thus turning the disk the shaft M is drawn outward and carried downward in slot a in the case by yoke N until pinion L engages with the smallest portion of the cone of gears, when motion is transmitted to the registering- 115 dials, as before.

This measure may be used without the auxiliary dials by removing them and shifting the main set around so as to gear with pinion K. In this case the locking-pin must be removed 120 from the ratchet-disk and a pawl be so placed in the reel as to hold the disk while the wheel is running back to wind the tape-line.

Having thus described my invention, what I claim as new, and desire to secure by Letters 130 Patent, is—

1. A lumber-measure having a reel and tape-line and two sets of registering-dials, one set designed to register an aggregate number of

measurements and the other set adapted to register a single measurement and then return to zero as the tape-line is withdrawn within the case.

5. 2. The combination, with the main set of dials, its actuating-train, and a pawl for preventing backward movement of said dials, of the auxiliary dials, actuating-gear therefor free to move in forward and backward directions, 10 the reel, a cone of gears secured to the reel, a broad pinion in mesh with the registering-train, and a shifting-pinion in gear with the cone and broad pinion, substantially as described.
- 15 3. The tape reel formed of two metallic disks having rims, as b' , and united together, and a hub, as b^2 , the rim of the reel being slit through, as at b^3 , and the web being perforated under the slit, as at b^4 , as shown and described.
- 20 4. The combination, with the sliding shaft, a portion of which is flat sided, and a sleeve enveloping the round portion of said shaft and

provided with a flange at its inner end and a stud fixed in the case, of a yoke one end of which has an elongated slot for fitting over the 25 flat-sided end of the shaft and so reduced in thickness as to receive the flange on the sleeve, the other end of the yoke being perforated for attachment to said stud, substantially as described, and for the purpose stated.

5. The combination, with the setting-disk recessed and perforated, as described, and a stud on the case for engagement with the recesses in the disk, of the spring on the under side of the case, provided with a pin which extends through the top of the case and engages the perforations in the disk, and a push-button for operating the spring.

In testimony whereof I affix my signature in presence of two witnesses.

FRANK S. BALDWIN.
